UNITED STATES PATENT OFFICE.

ROBERT R. WATSON, OF DETROIT, MICHIGAN.

DESIGN FOR A JAR-WRENCH.

SPECIFICATION forming part of Design No. 34,437, dated April 30, 1901.

Application filed March 16, 1901. Serial No. 51,569. Term of patent 7 years.

To all whom it may concern:

Be it known that I, ROBERT R. WATSON, a citizen of the United States, and a resident of Detroit, in the county of Wayne and State of Michigan, have invented and produced a new and original Design for a Jar-Wrench, of which the following is a full, clear, and exact description.

Reference is to be had to the accompanying drawing, forming a part of this specification, in which the figure is a perspective view of a jar-wrench, showing my design.

The invention relates to jar-wrenches or holders in which a flexible band is employed for engaging the body of the jar or can.

The design consists of a plate A, terminating at one end in a handle B and appearing

at one side with a transverse loop C and a pin D between the handle and the loop, the outer or free end of the plate A being rounded off, 20 as at E, as is plainly shown in the drawing.

Having thus fully described my invention, I claim as new and desire to secure by Letters Patent—

The design for the jar-wrench herein shown 25 and described.

In testimony whereof I have signed my name to this specification in the presence of two subscribing witnesses.

ROBERT R. WATSON.

Witnesses:

J. WILFRID WATSON,
JOHN T. CUSHING.
